UNITED STATES PATENT OFFICE.

FLORIAN WILLIAM STOCKER, OF HOBOKEN, NEW JERSEY.

PERISHABLE DIVIDING-PLATE.

1,131,872.

Specification of Letters Patent. Patented Mar. 16, 1915.

Application filed October 12, 1914. Serial No. 836,207.

To all whom it may concern:

Be it known that I, FLORIAN WILLIAM STOCKER, a citizen of the German Empire, and a resident of Hoboken, in the county 5 of Hudson and State of New Jersey, have invented certain new and useful Improvements in Perishable Dividing-Plates, of which the following is a specification.

This invention has reference to improvements in dividing plates for expansion joints for concrete curbing and the like and may also be used for sidewalk and other concrete work. Such dividing plates are usually 10 of metal and temporarily inserted between two concrete sections. When the concrete attains its initial or final set the dividing plates are removed whereby a slot is created between two adjoining concrete sections which permits of their expansion and 15 contraction.

Recognition of the necessity of providing certain means for securing definite joints as a protection against possible damage to the concrete sections, due to expansion and contraction led to the use of these so called 20 dividing plates. The dividing plates originally took the form of slotted metal strips, about $\frac{1}{8}$ of an inch thick. Some of those devices made of metal are held by long steel pins which provide a rigid, accurate and 25 durable means for separating the concrete sections. Flexible strips may be used for curves of any desired radius and means for making the form and dividing plates a single 30 unit are known.

Concrete curbing, sidewalks, concrete roads, etc., are laid in sections of suitable length and not continuously monolithic for several reasons: 1st. To accommodate expansion and contraction of the concrete. 2nd. To guard against breaking and damage in case of settlement of the sub-structure. 3rd. To facilitate sectional construction without removing temporary obstructions in the 40 right-of-way. The usual method employed to accommodate the foregoing is the employment of steel, wood, or iron dividers, or as they are called dividing plates of suitable shapes and thickness which are set or placed at intervals. After their removal the open joint or space displaced by it is filled with sand or other suitable material.

The disadvantages of this method are clearly shown when the following is considered: 1st. It is bad policy to leave the

plates in position until the concrete has attained its initial or final set, as it may bond together. The removal of the plates then certainly becomes at times dangerous and troublesome. 2nd. The premature removal 60 of the plates often destroys all edges which have to be replaced after the forms are stripped. 3rd. It prevents a continuous uninterrupted operation and saving of labor as the forming as well as the filling of the 65 joints with the filler, can only be made after the concrete has become sufficiently hard or set.

It is the purpose of the present invention to overcome the described defects and to 70 produce what I term perishable dividing plates which deteriorate under atmospheric influences and crumble up so as to allow of expansion and contraction of the concrete sections and the narrow opening 75 formed by the deterioration of the perishable plate will be filled up gradually by dirt or dust which settles therein. Thus the novel dividing plates which are perishable will be applied between the concrete sections and will remain therein so that no 80 removal is necessary whereby time and wages are saved. To attain this purpose the perishable plates consist of an organic substance such as saw dust, wood meal and the like, 85 a mineral substance such as common sand, and a glutinous binding material such as water soluble glue, gum tragacanth or the like. The proportions in which such materials are mixed may vary according to the 90 time they are intended to stand and according to the atmospheric condition prevailing in certain regions. The saw dust or wood meal, for instance, is mixed with some fine sand and some powdered glue and the 95 perishable plates are pressed into shape of the desired size. The surfaces of each plate are treated with an oily substance to prevent bonding with the concrete. Each plate may be made of one or more layers which 100 are pressed or joined together to attain sufficient strength or stiffness. A perishable plate thus produced is sufficiently strong to act as a dividing plate and elastic enough in itself to accommodate expansion and contraction; in the course of time, however, by atmospheric influence and action it will deteriorate and leave the desired joint. The glutinous substance is dissolved and the sand and saw dust settle in loose form. The 105

joint or slot naturally fills up by dirt or dust, thereby accomplishing all that is desired.

In order to render the invention entirely clear reference is had to the accompanying drawing in which:

Figure 1, represents in perspective view two sections of concrete with a perishable plate between them. Fig. 2, is a partial front view of the same on an enlarged scale. Fig. 3, illustrates in perspective view a perishable dividing plate. Fig. 4, is a similar view of a somewhat modified plate. Fig. 5, is a sectional view of a concrete section with 15 curb protector therein. Fig. 6, is a cross section on line 6—6 of Fig. 2. Fig. 7, is a similar view of line 7—7 of Fig. 2. Fig. 8 shows in perspective view an auxiliary member for setting the curb protectors on both 20 sides of the perishable plates.

Similar characters of reference denote like parts in all the figures.

In Fig. 1 of the drawing *a*, *b*, are two concrete sections between which a vertical dividing plate *c* is inserted. Each concrete section has a curb bar *d*. The perishable plate is of a shape and size corresponding to the shape and size of the side end surfaces of the concrete sections. The perishable plate shown in Fig. 3 has a body portion *c*¹ with straight top *c*² and an incision or slot *e* in the front top corner under an angle of 45°. The perishable plate illustrated in Fig. 4 has a body portion *c*³, a curved top *c*⁴ and an incision or slot *f* also under 45°. This incision or slot is required on account of the curb bars or protectors. In order to prevent any tilting motion of the curb bars an open shell *g* is inserted in the joint as 40 shown in dotted lines in Fig. 2, in section in Fig. 6 and in perspective view on an enlarged scale in Fig. 8. This shell passes through the slot in the perishable plate extending beyond the same on both sides and 45 when the curb bars are inserted under an angle of 45° the inner ends of their webs *d*¹ rest in the shell and the inner ends of their heads, shields or nosings bear against the

concrete whereby the tilting motion is avoided.

I claim as my invention:

1. A perishable dividing plate for an expansion joint for concrete construction and the like composed of a deteriorating substance, a finely divided mineral substance, and a deteriorating binding material.

2. A perishable dividing plate for an expansion joint for concrete construction and the like composed of a deteriorating organic substance, a finely divided mineral substance, and a glutinous organic binding material.

3. A perishable dividing plate for an expansion joint for concrete structures and the like composed of particles of a deteriorating organic material, a finely divided mineral substance, and a glutinous organic binding material.

4. A perishable dividing plate for an expansion joint for concrete curbing and the like composed of particles of a deteriorating organic material, a finely divided mineral substance, and a water soluble glutinous binding material.

5. In concrete curbing, sidewalks, roads and the like laid in sections, a perishable dividing plate composed of a deteriorating organic substance, a finely divided mineral substance and a glutinous organic binding material, said perishable plate being interposed between two adjoining concrete sections and remaining therein.

6. In concrete curbing, sidewalks and the like laid in sections, a permanent perishable dividing plate composed of a deteriorating organic substance, a finely divided mineral substance, and a glutinous organic binding material, said perishable plate having oiled surfaces to prevent bonding with the concrete.

Signed at New York, N. Y., this 1st day of October, 1914.

F. WILLIAM STOCKER.
